UNITED STATES PATENT OFFICE.

HERMAN G. KOTTEN, OF ENGLEWOOD, NEW JERSEY.

PNEUMATIC TOOL.

SPECIFICATION forming part of Letters Patent No. 660,857, dated October 30, 1900.

Application filed January 11, 1900. Serial No. 1,098. (No model.)

To all whom it may concern:

Be it known that I, HERMAN G. KOTTEN, a citizen of the United States, residing in the city of Englewood, county of Bergen, State of New Jersey, have invented a new and useful Improvement in Pneumatic Tools, which improvement is fully set forth in the following specification and accompanying drawings.

My invention relates to an improved construction of a pneumatic tool; and it consists more especially of the novel construction of piston or hammer having therein an unbroken exterior periphery, but provided with a longitudinally-extending recess which is always open to fluid-pressure, the cylinder of said tool being provided with ports and passages for admitting and exhausting the motive fluid to and from each end of the tool.

It further consists of novel details of construction, all as will be hereinafter fully described, and particularly pointed out in the claims.

Figure 1 represents a longitudinal sectional view of a pneumatic tool embodying my invention. Fig. 2 represents a view similar to Fig. 1, but showing the hammer thereof in an opposite position to that seen in said Fig. 1. Fig. 3 represents a sectional view of the hammer on line $\alpha\alpha$, Fig. 1.

Similar numerals of reference indicate corresponding parts in the figures.

Referring to the drawings, the motive fluid passes through the passage 1 and port 2 into the annular groove 3 of the cylinder, and when the parts are in the position seen in Fig. 1 the motive fluid flows through the longitudinally-extending recess 4 in the hammer 5 and passes through the port or ports 6, passages 7, and ports 8 to the chamber 9 at the chisel end of the cylinder. The hammer 5 will now move to the right into the position seen in Fig. 2, the portion 10 of the hammer leaving its bearing 11 and carrying with it the striker 12, which leaves the chisel-bushing 13. The parts now appear as seen in Fig. 2, the exhaust being permitted, when the hammer is moving toward the chisel, through the port 13, passage 14, and port 15 to the atmosphere, while the exhaust from the inlet end of the cylinder can take place at the proper time through the port 16, as is evident. The parts being now in the position seen in Fig.

2, the motive fluid passes through the longitudinally-extending recess 4, ports 17, passages 18, and ports 19 to the inlet end of the cylinder, whereupon the hammer 5 moves to the left of the position seen in Fig. 2, the exhaust taking place through the port 13, as already explained, as is evident.

I desire to call especial attention to the fact that I employ a solid hammer whose exterior periphery is of uniform diameter throughout, with the exception of the longitudinally-extending recess 4, whereby the life of the hammer and cylinder is indefinitely prolonged. The longitudinally-extending recess 4 is located on both sides of the hammer 5, and it will be apparent that it is much cheaper to manufacture hammers of this character than hammers having annular grooves therein, as has been done heretofore in this same class of invention. It will also be noted that by my construction, wherein I employ more passages 18 than passages 7, a rapid or accelerated movement will be imparted to the hammer toward the chisel end, the motive fluid flowing into the ports 6 through the annular passage 20 and into the ports 17 through the annular passage 21.

The inlet-piece 22 is preferably in threaded engagement with the cylinder, and the abutting faces of said cylinder and inlet-piece are provided with ratchet-teeth 23, which are engaged by the spring-pressed catch 24. The inlet-piece is further provided with an extension 25, having a hose-coupling connection thereon, whereby the tool can be readily coupled to and uncoupled from the hose which conveys the supply of motive fluid to the tool.

It will be apparent that slight changes may be made by those skilled in the art which will come within the scope of my invention, and I do not, therefore, desire to be limited in every instance to the exact construction I have herein shown and described.

Having thus described my invention, what I claim as new, and desire to secure by Letters Patent, is—

1. In a pneumatic tool, a cylinder, a solid hammer therein, having an unbroken exterior periphery, but provided with longitudinally-extending recesses on either side thereof, a groove in the inner periphery of said cylinder

always in communication with said recesses, an inlet-port in said cylinder leading to said groove, other grooves in the inner periphery of said cylinder on either side of said first- 5 mentioned groove, and ports and passages for admitting and exhausting the motive fluid from either end of said cylinder.

2. In a pneumatic tool, a hammer having an exterior periphery of a uniform diameter, 10 a longitudinally-extending recess in said hammer, said recess being always in communication with fluid-pressure through the groove 3 in the inner periphery of the cylinder, ports 6, passages 7, and ports 8 for admitting the 15 motive fluid to one end of said hammer, ports 17, passages 18 and ports 19 for admitting motive fluid to the opposite end of said hammer, the number of said last-mentioned ports being greater than the first-mentioned ports, 20 whereby a rapid movement toward the chisel end of the hammer is attained, grooves 20 and 21 on either side of said groove 3 and communicating with said ports 6 and 17 respec-

tively, and means for exhausting from each end of said hammer. 25

3. In a pneumatic tool, a cylinder, a hammer having a periphery of uniform diameter, a recess in said hammer, the chisel end of the latter being provided with a reduced portion 10 having a bearing 11, a striker 12 attached 30 to said reduced portion, a chisel-bushing 13 having an opening therein for the entrance of said striker, an annular groove 3 in said cylinder always open to fluid-pressure, and annular grooves 20 and 21 on either side thereof, which are alternately placed in communication with said groove 3 through the recess in said hammer, in combination with ports and passages leading in either direction from said grooves 20 and 21 to the ends of said 40 hammer. 35
